UNITED STATES PATENT OFFICE.

WILLIAM E. HALL, OF MONROE, MICHIGAN, ASSIGNOR TO FRED M. LONGNECKER, OF DELTA, OHIO.

TRAY MANUFACTURE.

Application filed March 19, 1923. Serial No. 626,016.

To all whom it may concern:

Be it known that I, WILLIAM E. HALL, a citizen of the United States of America, residing at Monroe, Monroe County, Michigan, have invented new and useful Tray Manufactures, of which the following is a specification.

This invention relates to the manufacture of articles out of sheet stock.

10 This invention has utility when incorporated for the production of food trays or paper dishes from fiber board, straw board or paper, say as supplied in continuous sheets.

15 Referring to the drawings:

Fig. 1 is a side elevation of a machine for carrying out the invention herein, parts being broken away;

20 Fig. 2 is a front elevation, from the left of Fig. 1, parts being broken away;

Fig. 3 is a bottom plan view of the top blank forming die;

Fig. 4 is a plan view of the bottom blank forming die;

25 Fig. 5 is a detail view of the stage of the folding of the cut blank, after the parts have come to the position in Fig. 2, with the cut blank in position for folding to commence;

30 Fig. 6 is a detail view as the folding operation is started;

Fig. 7 is a detail view of the anvil operating device for clinching the wire staples in the folded dish ends;

35 Fig. 8 is a detail view, at right angles to the showing in Fig. 6, showing the next stage of the folding operation thereafter;

Fig. 9 is a detail view of the fully folded dish or tray at the final stage of the folding 40 and in position in the folding dies;

Fig. 10 is a perspective view of a completed tray;

Fig. 11 is a plan view of a blank from which the tray is formed;

45 Fig. 12 is a plan view of the sheet feeding device;

Fig. 13 is a section on the line XIII—XIII, Fig. 12; and

Fig. 14 is a perspective view of the stock 50 engaging jaw of the feeding device.

A main base 1 is provided upon which is mounted brackets 2, 3 (Fig. 2), upstanding to carry main driving shaft 4. A continuously running belt 5 passes about pul-

ley 6 loosely mounted on the shaft 4. By 55 pulling handle 7, rod 8 therefrom to lever 9 is effective to pull in clutch 10 for connecting the pulley 6 to the shaft 4.

Stock supply.

60

Mounted on the shaft 4 adjacent the pulley 6 is small pulley 11 from which extends belt 12 to pulley 13 fast on shaft 14 carried by upright 15, adjacent a second upright 16. The upright 16 carries shaft 17 65 upon which is supported a roll 18 of strip material, say of fiber board 19.

On the shaft 14 is roll 20, the lower side of which extends into basin 21 in which is paraffine 22 maintained liquid by heating 70 coil 23. Opposing this driving roll 20 which is operating in the paraffine bath, is upper follower roll 24, effective for gripping the reach 19 of the sheet stock as drawn from the supply roll 18.

75 Steam line 25 which has valve 26 controlling the operation of the heating coil 23, has a branch line 27 with valve 28 to jets 29, disposed in proximity to the reach 19 between the supply roll 18 and the waxing rolls, which may be adjusted for moistening or steaming the stock, should such be brittle. This moistening is adjusted so that the folding of the dish or tray may not tend to fracture the stock, and is a 85 feature incidental to increased speed of operation in the putting out of articles of superior character.

Feeding device.

90

95 Strip 19 as passing from the paraffine rolls 20, 24, has wax coating 30 on its lower side. The driving or feed supply rate is such through the rolls 20, 24, as driven by the belt 12 that there is a slack or loop of the sheet stock between the upright 15 and table 31.

The shaft 4 is provided with pinion 4' in mesh with pinion 4" on shaft 4''' which extends through main frame 32 of the 100 blanking and folding machine on the base 1. Fast on the shaft 4 adjacent the side of the frame 32 remote from the pulley 6, is arm 33, having slot 34 in which is adjustably fixed wrist pin 35. From this wrist 105 pin 35 extends link 36 to upwardly extending lever 37 mounted on horizontal shaft 38 parallel to the shaft 4 and in the upper

portion of the frame 32. This lever 37 has intermediate slot 39 in which pivot pin 40 is adjustable to different positions in carrying link 41 horizontally extending rearwardly to pivot pin 42 adjustable to different fixed positions in slot 43 of upstanding lever 44 having lower fulcrum 45 mounted by the frame 32.

This lever 44 is rigidly connected through 10 its fulcrum shaft 45 with lever 46 upon the opposite side of the frame 32 to extend above the plane of the table 31. Each of these levers 44, 46, has a slot 47 near its upper free end, along which is adjusted 15 transverse shaft 48. Adjacent each side of the table 31, the shaft 48 has a loose arm 49 (Fig. 12), which arms are held spaced apart by collars 50, as held by set screws 51 fast with the shaft 48. Each of these 20 arms 48 is inclined downwardly to have its free end carry a roller 52 riding along track 53 on each side of the table 31. In the arc throws or swinging of the levers 44, 46, these rollers 52 are held in contact with the 25 tracks 52. To this end the shaft 48 has central pin 54 about which is looped central portion of helical torsion spring 55 having free ends 56 extending to shaft 57 carrying the rollers 52. This shaft 57 is accordingly 30 held to ride at a constant distance from the table 31. Loosely mounted on this shaft 57 and extending away from the shaft 48 is an arm, claw or engaging jaw 58. Fixed on the shaft 57 is a collar 58' from which 35 extends torsion helical spring 59 to this claw 58 for yieldably holding or throwing this claw downward toward the table 31.

This jaw (Figs. 13, 14) 58, has rounded free end 60 which will tend to prevent the 40 strip sheet stock 19 from buckling or rolling. The under side of this arm or jaw 58 has depending lugs 61, 62. A set screw 63 may engage with this lug 62 for mounting en- 45 gager 64, shown as having serrations or teeth on each of the four sides thereof. There is thus a convenient means for resetting this tool to expose a different side, as one becomes dulled in engaging the stock, for definite feed distance pulls thereof across 50 the table 31 to supply the stock, as paraffined on the lower side, to the blaner.

The blaner.

The frame 32, above the shaft 4, carries 55 downwardly, facing plate 65 as anchored in position by bolts 66 engaging the frame 32. This plate 65, on its lower side has attached thereto upper or tray outside blanking die 67 (Fig. 3). This die 67 has scoring pro- 60 jecting edges or knife portions 68. In the pattern of the blaner for oblong trays with continuous side wall, it is preferred herein to have this member 67 of the blanking die pair have seats to oppose scoring 65 determining edges, as well as blank cutting

out knives of the opposing die. The disk or tray bottom may be determined by sides 69 and ends 70, to give it a rectangular form. Approximating the direction of the sides 69 extended, or slightly diverging from the 70 scoring edges 68 are seats or grooves 71 from the corners produced by the grooves 69, 70. Diverging from the groove 71 and on the opposite side thereof from the scoring edge 68, is groove 72. The side of the die 67 75 toward the oncoming strip 19 of stock, has a groove 73 extending beyond the grooves 72 to diverging grooves 74. The opposite corners of this die carry knives 75.

Opposing this fixed blaner die 67 is a 80 movable blaner die. Mounted on the shaft 4" just outside the frame 32 and on each side thereof, is an eccentric 76, for operating upwardly extending connecting rod 77 to crosshead 78 movable up and down in guides 85 79 in the frame 32 and carrying on its upper side blanking die 80 to act upon sheet stock as passing thereover, by forcing such stock against the blanking die 67. This die 80 has grooves 81, 88, opposing the scoring 90 blades or edges 68, 75, and has scoring edges 82, 83, 84, 85, opposing the grooves or seats 69, 70, 71, 72. The only cutting is effected by knives 86, 87, opposing the grooves 73, 74.

Spring pins 89 in the blanking dies 67, 80 95 (Figs. 3, 4), as acting upon paper as being blanked from a strip, loosen such paper or stock from the die as the dies separate after having come together to effect the 100 scoring and cutting operations. The blank is thus kept from being packed into either die. The feeding device, as delicately and accurately adjusted in its feeding drive distance, causes the strip paper stock as coming to the blanking die to force the preceding portion or blank 90 past the blanking dies to the position for folding. At this position for folding, the knives 86, 87, effect 105 final severing of the blank.

The blank.

The blank 90 (Fig. 11) on its lower or tray interior side, has tray bottom 91 bounded by scorings 92, 93, on the inside. Each corner 94, has scoring 95, 96, therefrom 115 on the tray interior, and scoring 97 on the tray exterior. These scorings 97, with the scorings 93 determine inner tongues 98, backed by folds 99, while cut corners 100, determine the tray end height, which preferably has short edge 101 as an extension of tray side upper edge 102 to pass the scorings 95.

The folder.

From the main frame 32 there rises pedestals 103 to carry upper cross frame 104 from which centrally depends member 105 as fixed by bolts 106 having rigid connection with the frame 104. The lower portion of 120

this member 105 carries socket or tray exterior forming folder member 108. In the upper portion of the member 105 is compression spring 109, normally thrusting stem 110 downward, to hold U-shaped auxiliary folder member 111 at its lower end out of seat 112 in the upper main folder member 108.

The drive for the folder is from the main 10 drive shaft 4''' by way of the gear 4" in mesh with gear 113 on shaft 114, carried by brackets 115, 116, 117, on the base 1, to protrude through the frame 32, parallel with the shaft 4'''. Intermediate the bearings 15 provided by the brackets 116, 117, this shaft 114 has crank 118, from which upwardly extends connecting rod 119 with spring box 107 to yieldably reciprocate vertically member 120 in guide 121, carried by the main 20 frame 32.

The upper end of this member 120 carries tray interior forming folder member 122, to be upwardly thrust into the pocket or socket member 108, to force the auxiliary folder 25 member 111 into the seat 112.

In the folding operation, the loose or auxiliary folder member 111 engages the outer sides of the tongues 98 to bend such inward, the feeding device having thrust the 30 blank 90 into position between the folder members with its front edge against stops 123 fixed with the frame 32, and said blank held from falling by the member 122. As the tongues 98 are folded inward, there is a 35 tendency for the sides to bow outward which is assisted by starting to fold the sides before the tongue, and this is further controlled as the tray sides ride into straight portions 124 (Fig. 8) of the upper folder 40 member 108, and then are shaped by being thrust against tapered side wall forming walls 125 of the high wall pocket member 108 of the folder. The directing action for the tongues 98, shapes the ends for folds at 45 the scorings for the folds 99 to be positioned back of the tongues 98 in the completely folded tray or dish.

Wire feed device.

50 The holding of the folded dish into shape is herein effected by stapling or fastening by wire. Such wire staples are provided one at each end of the completed dish. Extending forwardly from the frame 32 and approximately at the plane of the table 31, is a pair of arms 126, carrying at their free ends upward pins 127. On each pin 127 is a spool 128 for a coil 129 of wire from which extends reach of wire 130 to pass through 55 guide duct 131 between feed rolls 132, 133. The lower feed rolls 132 are on shaft 134, parallel to shaft 135 carrying the feed rolls 133. Adjusting devices 136 determine the 60 gripping action of the upper rolls upon the wire as passing over the lower rolls. Auxil-

iary bracket 137 mounts these wire feed elements fixed with the frame 32, through plate 138 carried by the upper cross frame 104.

The drive for this wire supply or feed is from the shaft 114, which at its end remote 70 from the gear 113 has slotted arm 139 (Figs. 1, 2) as a crank for adjustable wrist pin 140 to upwardly extending connecting rod 141 engaging reciprocable bar 142 slidable in guides 143, 144, carried by the frame 32, and 75 frame extension 103. This bar 142 has rack 145 in mesh with pinion 146 on the shaft 134 (Fig. 1). Adjustments at the wristpin 140 determine the feed steps in progressing the wire 130 to the stapling devices. 80

Stapling devices.

Mounted on the shaft 114 outside the bearings 116, 117 (Fig. 2) is a pair of eccentrics 147. From each eccentric 147 upwardly extends connecting rod 148 to lever 149 having after portion fixed for pivoting at fulcrum 150 mounted in the frame 32. The forward free end of each of these levers 149 has upwardly extending therefrom connecting rod 90 151 to vertically reciprocate multiple cam member 152 in guide 153 of the frame 32. These cams are timed to reciprocate in cutting off the wire 130 into lengths to form 95 staples, bend such staples, and thrust such 100 from the outside through the folds 99 and the tongue 98. The staple is wide enough to catch the two folds at each end.

The crank 118 of the shaft 114, has a cam 154, coacting upon the upper portion of the 105 crank throw with rod 155 in the member 120 (Fig. 7), to move such rod 155 upward, and thereby force outward staple clinching plungers 156, in completing the dish forming operations. In the continuation of the machine 110 operations, as the folder 122 descends, the spring 109, acts upon the auxiliary folder member 111 to thrust the formed dish out of the socket of the member 108. As the folder 122 descends fixed pin 157 catches the back 115 edge of the dish, and with the folder 122 continuing its descent, the dish is tilted off the folder and falls upon chute 158, there to be taken by conveyor 159 for packing into cartons, or such other disposition as may be desired. This conveyor is driven by belt 160 from the shaft 114.

The dish or food tray 161 as completed has its side walls continuous, and the assembly 120 or form is maintained by staples 162 at each end to engage the pair of outer folds and the inner tongue. The inner ends of the staples 162 are clinched or bent back into the stock of this water-proofed, or paraffine coating lined food tray. The straight lines of the blank outer contour determine a definite shape, so that these taper walled trays may 125 snugly nest for compact packing, and retention of shape. In the forcing of the trays into nesting relation, there is mutual rein- 130

forcement in holding the trays to form as to a common size thereof. They are accordingly articles which may be compacted into straight rows or stacks in definite quantities 5 even in cartons, and instead of having rupturing tendency, snugly fill the carton and while quite heavy still co-operate to give the carton rigidity.

In operation, a supply roll 18 of stock of 10 strip material is placed on the uprights 16, such stock being of a width to approximate the maximum dimension of the blank 90. If such stock be pliable, it is not, or may not be necessary to temper it by the steam before 15 passing it in continuous travel between the rolls 20, 24, to have the lower roll 20 apply a coating of paraffine wax to the lower side thereof, thereby to waterproof the stock on the side which is to form the dish interior. 20 The loop in the strip 19 between the waxing rolls and the blanking and folding machine unit is to permit the intermittent feeding of the stock to the blanker without placing a strain upon the stock as passing the 25 waxing rolls. As the machine operates continuously, the levers 44, 46, rock to and fro, to shift the carrier along the tracks 52, in effecting intermittent thrusting of the sheet stock over the table 31 upon the lower blank- 30 ing die 80. During the recover travel of the carrier, this die 80 moves upward a slight distance against the fixed upper blanking die 67 to effect shearing off and complete scor- 35 ing of a section of the strip stock in forming blank 90 and rejecting small triangular marginal portions as cut from the stock by the knives 87. The succeeding cycle of operation of the machine, causes the stock as thrust over the blanking dies by the feeder, 40 to engage the blank 90 as loosened from the blanking dies by the spring pins 89, and shift such blank 90 into position over the lower folder member 122, which die member 122 is traveling upwardly and thrusts 45 the blank 90 as it is finally cut free of the strip into the socket of the upper or opposing folding die member 108, effecting the bending inward of the tongues 98 after straightening and initiating folding of the 50 tray sides, locating the folds 99 against the outer sides of the tongue, and then stapling by a single staple the two folds 99 at one end with the tongue 98 at such end of the tray, and clinching the staple ends into the 55 tray stock on the tray tongue inner side. As the plunger folder member 122 descends, the tray 161 is toppled out upon chute 158, to be carried away from the machine by conveyor 159. 60 The features of tray form, and stock supply and feeding thereof, together with the manner of scoring and folding, permit of accurate registry throughout positively at high speeds of operation, with the turning 65 out of trays in sizes of one half pound to

five pound containers at rates from 120 to 150 per minute. These features are accordingly inter-related features of great value in quantity production hereunder.

What is claimed and it is desired to secure 70 by Letters Patent is:—

1. The method of producing a tray from continuous sheet stock, including the defining of a form, and the scoring of the form in a line on one side of the stock, and simultaneously scoring the form in a line on the opposite side of said stock, said lines in the direction of their extent diverging from each other. 75

2. The method of producing a continuous 80 side wall tray from sheet stock, including the scoring of a form for a polygonal bottom and three lines from each corner of said bottom, one of said score lines from each corner extending toward a score line from 85 an adjacent corner and being on the opposite side of said sheet stock from the remaining score line from such corner.

3. The method of producing a tray from 90 sheet stock, including the simultaneous scoring of the stock in a continuous line for a form on one side for a fold one way and scoring in a different continuous line on the opposite side for a fold the other way, and effecting said foldings in said opposite directions on said lines to produce at one line a corner inside the tray and at the other line a corner outside the tray. 95

4. The method of producing a tray from a 100 form of sheet stock, including the scoring of the form for providing a blank having said scorings define sides and a pair of inner tongues each inward from an edge of the blank as spaced by said sides of the tray, and the folding of said blank by first bending said sides inward and then thrusting said tongues inward. 105

5. The method of producing a continuous 110 side wall tray for a sheet of material by scoring on one side thereof to define a tray bottom, and from each corner of said bottom and on the same side forming one scoring to approximate a line with said bottom scoring, and forming a second scoring to diverge therefrom, and on the other side of 115 said sheet which is to be the tray exterior forming a third scoring from each corner diverging from the second scoring whereby the side of the sheet at the scorings are folded toward the respective scorings in forming at each scoring a re-entrant angle. 120

6. The method of producing a continuous 125 side wall tray having general rectangular form, with corners beyond which the outer edge of the tray sides extend, embodying effecting a rectangular scoring of a sheet for defining on the tray interior the tray bottom, additionally forming a first scoring diverging from each corner away from said bottom scoring direction at said respective 130

corners, said first scorings extending as to two thereof to spaced points along a common outer edge and as to an additional two thereof to spaced points along an opposite outer edge, and on the opposite or tray exterior side of said sheets forming a scoring to each corner of said bottom, these outside scorings each being from a margin of the tray and extending toward each other in pairs to define inner tongues for the tray.

7. A pair of scoring dies for defining opposite folding lines for sheet material, one of each dies having ribs and grooves and the other die having grooves opposing said ribs of the one and ribs opposing the grooves of said one, each of said ribs defining an in-

side corner folding line, for the one die upon one side and for the other die upon the opposite side of the material as acted upon by the dies, the line of direction of grooves on one die diverging from the line of direction of grooves on the opposing die. 20

8. A tray machine die for a continuous side wall tray embodying scoring ribs for tray defining bottom and corner inside folding lines, and an opposing die having scoring ribs for tray tongue defining lines foldable as a re-entrant corner to overlap said tongues inside the tray toward the tray corners. 25

In witness whereof I affix my signature.
WILLIAM E. HALL. 30
